UNITED STATES PATENT OFFICE.

ROSS PHILLIS, OF SPRINGFIELD, OHIO.

WIRE FENCE.

SPECIFICATION forming part of Letters Patent No. 557,017, dated March 24, 1896.

Application filed August 23, 1895. Serial No. 560,258. (No model.)

To all whom it may concern:

Be it known that I, ROSS PHILLIS, of Springfield, in the county of Clark and State of Ohio, have invented a new and Improved Wire Fence, of which the following is a full, clear, and exact description.

This invention relates to wire fences, and has for its objects to provide novel braces or stay-pieces for the wires comprising the fence, and also to afford reliable means for securing the fence-wires on supporting-posts which will permit expansion and contraction of the wires and take up slackness occasioned by expansion of said wires.

15 The invention consists in the novel construction and combination of parts, as is hereinafter described and indicated in the claims.

Reference is to be had to the accompanying drawings, forming a part of this specification, 20 in which similar characters of reference indicate corresponding parts in all the views.

Figure 1 is a side view of a fence-post, fence-wires thereon, and features of the improvement engaging the fence-wires. Fig. 2 is a 25 transverse sectional view substantially on the line 2 2 in Fig. 1. Fig. 3 is an enlarged sectional side view of part of a fence-post and improved means for supporting fence-wires thereon. Fig. 4 is a plan view of one fence- 30 wire stay engaging a fence-wire, shown in part. Fig. 5 is a side view of a part of a wire-fence panel, the wires of which are spaced apart and braced by stays slightly differing in construction from those shown in Fig. 1; 35 and Fig. 6 is a plan view of a fence-wire stay of the form shown in Fig. 5.

The wire fence embodying the improvements may be composed of any preferred number of wire strands 10, which are sustained 40 at their ends in spaced order on posts 11, thus forming a fence-panel that is of a suitable length. One essential requisite for the proper support of the fence-wires on their sustaining-posts consists in providing an attachment 45 for the wires to the posts which will allow the wires to contract in cold weather and avoid strain due to such contraction, which if not compensated for will rupture the wires. To this end the spring attachments for the ends 50 of the wires (clearly shown in Fig. 3) are provided, one for each terminal of a wire, and each consists of a bolt 12, having a ring-eye a

at one end, which is coupled to a similar eye on the end of the fence-wire. The bolts 12 are respectively passed through perforations 55 in the post-body, which perforations are properly spaced apart parallel with each other, all passing through the same sides of the post.

The bolt-receiving perforations are counterbored of a like depth from what may be 60 considered the outer side of the post, which produces an annular space around each bolt when the latter are inserted and passed through the post, first entering the smaller diameter of the perforation and then extending 65 through the counterbore b and beyond the latter sufficiently to first receive the washer c and then the nut d. Before the washer and the nut are placed on each bolt 12 a strong spiral spring 13 is mounted on the same, said 70 springs having such proportionate length that they will be slightly compressed when the fence-wires that are attached to the eyes of the bolts 12 are drawn taut and the washers c have enforced contact with the side of the 75 post.

The preferred form for the fence-wire stay, as shown in Figs. 1, 2 and 4, consists of a flat strip of metal 14, provided for each stay, said strip having spaced loops e formed in it, which 80 loops are all open at the same side of the strip, and their spaced separation is such as will permit the loops to severally engage with the fence-wires, each loop receiving an appropriate fence-wire, as clearly represented in Figs. 85 1 and 2. In the projecting looped portions e vertically-aligning perforations are formed to permit a keeper-rod 15 to be downwardly inserted, passing through all the loops, as clearly shown in Fig. 2. This form of loop 90 and hook forms a lock on the fence-wire, which prevents it from being moved up or down or lengthwise when pressed against by animals, as, if one of the loops is moved, the loops above and below it will lock to the fence-wires, and 95 this is a very essential feature of the fence. The stays and rods can be removed at will without injury to the fence-wires or the stays.

It will be seen that from the position given 100 the keeper-rod for each stay-piece 14 the said rod will impinge upon each fence-wire 10 and bind it within the loop e it occupies, and the series of fence-wires in a panel will be firmly bound in spaced condition if a suitable num-

ber of the improved fence-wire stays are provided therefor.

In Figs. 5 and 6 the improved fence-wire stay is shown as formed of wire rods instead of a metal strip, the same consisting of two wire strands 16, which are twisted together, having integral loops *g*, formed at proper intervals in pairs, which loops are adapted to receive the fence-wires 10 in a manner similar to the loops *e*, and also permit the introduction of the upright keeper-rods 15 between the loops, which rods when inserted will hold the fence-wires in the wire loops *g*.

The keeper-rods are each furnished with a ring *h* that is formed on the upper end of the same, and said rings have sufficient diameter to permit the insertion of the angularly-bent upper end portion of the stay-pieces 14 through the ring and beyond it, as clearly shown in Fig. 4, the projecting end of the stay-piece being preferably cut to afford two prongs *i*. In a like manner the stay-piece formed of the wire strands 16 is bent at the upper ends of said strand to produce two prongs *n*, one on each strand, and said prongs are spread apart to provide barbs.

The provision of the barbs *i* or *n* on the upper ends of the stay-pieces 14 or 16 insures locking the keeper-rods 15 from removal, and the barbed formations also prevent animals from pushing against the stay-pieces of the fence when the stay-pieces are locked by the keeper-rods.

Having thus described my invention, I claim as new and desire to secure by Letters Patent—

1. In a wire fence, the combination with supported wires vertically arranged in spaced order, of a plurality of brace-pieces, each consisting of a flat metal strip having open loops formed thereon and projecting from the same side of said strip, the loops being perforated in vertical alignment, and a keeper-rod for each brace-piece, having a ring on its upper end and passing through and closely fitting the perforations in the loops after the latter are occupied by the fence-wires, and whereby said wires are bound in the loops, the upper end of the brace-piece being laterally bent and passing through the ring of the keeper-rod, retaining said rod locked in the brace-piece, substantially as shown and described.

2. In a wire fence, the combination with supported fence-wires spaced apart in a vertical plane, of brace-pieces for said fence-wires, each having a series of loops spaced apart to receive the fence-wires and open on the same side of the brace-piece, the loops being perforated in alignment, a keeper-rod for each brace, passing through the perforations in the loops after the latter are occupied by the fence-wires, said keeper-rod having a ring on its upper end, and a laterally-bent formation on the upper end of the brace-piece fabricated to provide barbs and passing through the ring of the keeper-rod, substantially as described.

ROSS PHILLIS.
